UNITED STATES PATENT OFFICE.

CLAUDE DORNIER, OF FRIEDRICHSHAFEN, GERMANY, ASSIGNOR, BY MESNE ASSIGNMENTS, TO DORNIER-METALLBAUTEN GESELLSCHAFT MIT BESCHRÄNKTER HAFTUNG AND CLAUDIUS DORNIER, OR FRIEDRICHSHAFEN, A. B., GERMANY.

AIR PROPELLEF.

Application filed June 28, 1920. Serial No. 392,559.

(GRANTED UNDER THE PROVISIONS OF THE ACT OF MARCH 3, 1921, 41 STAT. L., 1313.)

To all whom it may concern:

Be it known that I, CLAUDE DORNIER, a citizen of the German Empire, residing at Friedrichshafen, Germany, have invented 55 certain new and useful Improvements in Air Propellers (for which I have filed an application in Germany Sept. 2, 1916), of which the following is a specification.

My invention refers to air-propellers with 10 hollow blades. Such propellers can be obtained by flattening by pressure a hollow tubular body at its ends after the manner of propeller blades and by developing the center as the boss of the screw. The subsequent transformation of a tubular body into 15 a two-bladed screw, however, can only be achieved with difficulty with the desired accuracy. On the other hand propellers are known in which the hollow blades are 20 mounted on blade-supports fixed to the boss of the screw. In this latter type of construction, however, there exists the danger of the blades being hurled off by the centrifugal force.

25 It is the object of my present invention to avoid the drawbacks of both types of construction. This aim is achieved by the propeller being composed of several interior and exterior parts stretching at least approximately from one blade edge to the other 30 and by the blade laminations as well as the arms being utilized as supporting parts. Accordingly the object of the invention consists in an air-propeller with hollow 35 blades in which two blade laminations stretching continuously from one blade edge to the other, and several pairs of stays or rolled section girders also stretching from end to end, are employed. According to the 40 invention the section girders situated on the outside, at the same time, serve as transition bodies for the transition from one blade lamination to the other. In this manner great strength of the finished propeller 45 can be achieved with easy manufacturing and great accuracy of the various parts.

The manufacture of an air-propeller becomes particularly advantageous, if the parts of the blades situated outside the inner 50 pair of stays are made lighter than the parts inside the pair of stays. As the middle part of the propeller which is stayed

by the girders, possesses great strength owing to its box girder's shape, the blade-ends which are not fastened together yet, 55 can be bent up elastically a little without difficulty, thereby rendering the inner stays easily accessible for riveting tools, etc. Besides, the blade becomes lighter.

The drawing attached to this specification 60 and forming part thereof, illustrates an example of a modification of the present invention in a purely diagrammatical manner. In the drawings:

Fig. 1 is a plan view of the propeller and 65

Figs. 2-5 are cross-sections at various distances from the axis of the propeller, on lines A—A, B—B, C—C, and D—D, respectively.

Fig. 6 is a repetition of Fig. 3 on a larger 70 scale.

In the case exemplified the propeller consists of the boss of the screw, a suction and a pressure blade lamination continuous in both cases, the inner stays, the outer stays 75 and two boom butt straps.

Manufacture can take place in the following manner: First the bosses of the screws are riveted together with the two inner stays and each blade with the pertinent boom butt strap. Thereupon the one blade lamination is riveted to the boss of the screw as well as the flanges of the continuous inner stays. Then the second blade 80 is riveted on, whilst holding up takes place 85 from the sides or the ends. Finally the outer stays are riveted in. For these the rivets are riveted right through, whilst for the inner stays the rivets only connect one blade lamination to the supporting stay 90 flange at a time.

Mostly the pressure side will be plane or only slightly vaulted. The pressure blade lamination can therefore be bent up during the riveting beginning from the boss of the screw, thus enabling specially easy holding-up. It is useful to make the blade laminations and stays of light metal, whilst steel is preferable for the boss of the screw. The thickness of the blades can decrease from 95 the boss of the screw towards the points. It is advisable to give the inner stays a U-shaped cross-section with the flanges pointing outwards. In the case of very large

dimensions compound sections or box beam sections may also be employed. The rivet heads on the outer surface must be counter-sunk. The boom butt straps can also be left out. A special advantage of this construction lies in the fact that small screw bosses can be employed.

I claim:

1. In a hollow propeller in combination, 10 two metal plates suitably united at their edges and extending each from the outer end of one blade to the outer end of the other, and a plurality of channels inserted between and fixed to said blades and ex-

tending longitudinally thereof from one end 15 to the other.

2. In a hollow propeller in combination, two metal plates suitably united at their edges and extending each from the outer end of one blade to the outer end of the other, 20 and a plurality of channels inserted between and fixed to said blades and extending longitudinally thereof from one end to the other, the middle portions of said plates being thicker than the portions adjoining 25 their longitudinal edges.

In testimony whereof I affix my signature.
CLAUDE DORNIER.
